(57) **CLAIM**

The ornamental design for a flooring clip, as shown and described.

DESCRIPTION

The claimed flooring clip is used with a series of similar clips along the upper edge of a timber joist, the two "U" clips being adapted to receive and support piping, e.g., of plastics, of a central heating system.

FIG. 1 is a front perspective view of a flooring clip showing our new design;

FIG. 2 is a top plan view thereof;

FIG. 3 is a front elevation view thereof; and,

FIG. 4 is a side elevation view thereof.
